US00D759667S

(12) **United States Design Patent**
Kim et al.

(10) **Patent No.:** US D759,667 S
(45) **Date of Patent:** ** Jun. 21, 2016

(54) **DISPLAY SCREEN OR PORTION THEREOF
WITH GRAPHICAL USER INTERFACE**

(71) Applicant: **Samsung Electronics Co., Ltd.,**
Suwon-si, Gyeonggi-do (KR)

(72) Inventors: **Na-Ri Kim**, Seoul (KR); **Tae-Young Ha**,
Seoul (KR)

(73) Assignee: **SAMSUNG ELECTRONICS CO.,
LTD. (KR)**

(**) Term: **14 Years**

(21) Appl. No.: **29/496,343**

(22) Filed: **Jul. 11, 2014**

(30) **Foreign Application Priority Data**

Jan. 13, 2014 (KR) 30-2014-0001900

(51) **LOC (10) Cl.** **14-04**
(52) **U.S. Cl.**

USPC **D14/485**

(57) **CLAIM**

We claim, the ornamental design for a display screen or portion thereof with graphical user interface, as shown and described.

DESCRIPTION

The FIGURE is a front view of a display screen or portion thereof with graphical user interface, showing our new design.

The broken lines represent portions of the display screen or portion thereof with graphical user interface and form no part of the claimed design.
